METHOD OF CREATING DESIGNS FOR
CANDLES

Irineos Cassimatis, Gary, Ind., assignor of one-half to Harry E. Strategos, Chicago, Ill.

Application December 14, 1936, Serial No. 115,733

3 Claims. (Cl. 18—58)

My invention relates to a method of creating candles, and the like with markings and designs, and particularly in different colors on their outer surfaces.

Makers and users of candles, and the like have long wanted to use markings, designs and different colors on candles to indicate the different seasons, to conform to desired color schemes and decorations, to bear insignia and combination of colors of family, country, organization, trade origin and the like. Efforts at such effects have been attempted by gluing plaster of Paris, paper or other extraneous substances to a candle. Such effects are expensive, cumbersome, inefficient and often interfere with the burning of the candle. Among the objects of my invention is to make a candle bearing as an integral part of the candle a design or marking in black or different colors appearing on the outer surfaces thereof, and which will in no way interfere with the normal burning of the candle. Another object is to disclose a method for creating such a design bearing candle, and which method is practical, inexpensive and expeditious.

While I have shown herein my preferred method, embodiment and means for securing said embodiment, yet I wish it understood that the same are susceptible of modification and change without departing from the spirit of my invention.

Referring to the drawings, Fig. 1 is a perspective view of a strip of celluloid with a stencil superimposed thereon and a roller applying ink through the stencil to the strip with part of the strip already having received the marking; Fig. 2 is a perspective view of the folded strip of celluloid about to be inserted into the resilient mold, with the markings of the strip on the inside; Fig. 3 is a perspective view of the wick and base which are inserted into the tube; Fig. 4 is a perspective view showing the pouring of the candle making material into a funnel into the mold; Fig. 5 is a perspective view showing the placing of the mold into a cold bath; Fig. 6 is a perspective view of the loosening of the thumb nuts on the tube; Fig. 7 is the removing of the candle; Fig. 8 is a perspective view of the completed candle.

The preferred method of my invention comprises taking a strip of resilient and non-porous material 10 such as celluloid or the like, and placing a stencil 11 thereon so that I may roll a printer's roller 12 containing marking material such as ink or the like thereon for applying markings to the portions of the material 10 ex-

posed by the stencil 11. The stencil 11 may permit lines or any kind of symbols or markings 13 to be formed on the material 10 by the ink or any other coloring matter applied by the roller 12. It is of course obvious that this step of the method may be repeated more than once, so that different stencils may be used for creating different markings in the same or different colors.

I then fold or roll the strip 10 so that the wet marked portions 13 are on the inside of the roll 14, and before the markings can dry the roll is immediately placed into a device 15. This device 15 has an open top 16 and an open bottom 17 and is formed of a pair of tubes, the outer tube 18 not quite inclosing the inner tube 19; said tubes positioned so that the longitudinal edge 20 of tube 18 forms an opening 21 substantially opposite the opening 22 formed by the longitudinal edges 23 of tube 19. In this way the opening 21 is covered by tube 19 and opening 22 is covered by tube 18 at substantially the respective middle portions of said tubes. Said construction affords considerable resiliency. A plurality of spaced straps 24 surrounding the tubes may be tightened by thumb nuts 25 for making the inside tube perfectly round, as well as the roll 14 therein. The thumb nuts may be loosened as later disclosed.

I then run a wick 38 through the cylinder 15, carrying at one end a base 26 having a substantially coned shaped interior. The base 26 fits and closes by friction grip the open bottom 17, when I tighten the thumb nuts 25.

I then place funnel 27 so that it fits into and covers the open top 16 of the cylinder 15, and I then pour therein a desired content of hot molten candle making material 31 such as paraffin, tallow, wax or the like.

I then place the cylinder 15 in a bath 28 of cold water or the like and leave it there a sufficient time to cool the contents.

I then remove the cylinder 15 from the bath, remove the base 26, loosen the thumb nuts 25, and pull out a newly formed candle and material 10 by the funnel. I then cut the wick from the funnel and the material 10 falls away leaving candle 29 having markings 30 appearing on its exterior.

My material 10 is sufficiently resilient and non-porous so as to pass off the markings to the outer surfaces of the candle and to also create a desirable and unusual luster to the markings.

My device 15 is both a mold for shaping the poured in melted substance and is also with my inserted strip a marking applicator. At the same

time that my device shapes the substance poured therein it is also applying the marking on the material 10 to the outer surface of the shape forming substance.

5 5 It is also within the contemplation of my invention to have the material 10 molded into any desirable shape so that it might be inserted into the device 15 in other forms than merely being in the shape of a roll.

10 10 Having thus described my invention, I claim:

1. The method of creating a candle having ink markings on its outer surfaces comprising taking a strip of nonporous resilient material, applying desired wet markings in ink thereto, rolling said

15 15 strip so that the wet ink markings are on the inside of the roll, immediately placing said roll in a cylinder, pouring hot melted candle forming stock in said cylinder while the ink on the roll is still wet, solidifying said stock, and re- 20 20 moving the candle shaped by said cylinder and bearing surface markings from contact with the wet ink on said roll.

2. The method of creating a candle having ink markings on its outer surfaces comprising taking a strip of nonporous resilient material, applying desired wet markings in ink thereto, rolling said

25 25 strip so that the wet ink markings are on the inside of the roll, immediately placing said roll in a cylinder having an open edge, tightening

30 30 the cylinder so as to close the open edge, placing a wick and base in said cylinder, pouring hot

candle forming stock in said cylinder while the ink on the roll is still wet, placing said cylinder in a bath to solidify the contents, loosening pressure on the cylinder, and removing the candle shaped by said cylinder and bearing surface 5 markings by contact with the wet ink on said roll.

3. The method of creating a candle having ink markings on its outer surface comprising taking a piece of celluloid, applying wet ink to portions of said celluloid to form a desired design, rolling the celluloid to form a tube with the wet markings on the inside of the tube, placing the tube in a cylinder having an open top and an open bottom and an open longitudinal edge, tightening the cylinder to close the open longitudinal edge, placing a candle wick in the cylinder, placing a base at the bottom of the cylinder to close the same, placing a funnel in the open top of the cylinder, pouring hot candle forming stock in said funnel so as to substantially 10 15 20 25 fill the cylinder while the ink on the inside of the tube is still wet so that as the hot stock contacts the wet ink the ink is transferred to and forms a design on that portion of the stock that forms the outer surface of the candle 20 25 formed by the stock, solidifying the contents of said cylinder, loosening pressure on the cylinder and removing the candle bearing surface ink markings.
